UNITED STATES PATENT OFFICE.

JOHN WALKER, OF INDIANAPOLIS, INDIANA.

TRAVELING CRANE.

SPECIFICATION forming part of Letters Patent No. 250,312, dated November 29, 1881.

Application filed August 27, 1881. (No model.)

To all whom it may concern:

Be it known that I, JOHN WALKER, of Indianapolis, in the county of Marion and State of Indiana, have invented certain Improvements in Traveling Cranes, of which the following is a specification.

This invention relates to a traveling crane in which the hoisting apparatus, instead of being located upon the girders adapted to be moved longitudinally of the building, is placed upon an extension of a wheeled frame, and near the floor, in order that the longitudinal and transverse movements of the hoisting apparatus may be effected directly by hand, and without the interposition of chains and winding devices, as will hereinafter fully appear.

In the further description of my invention which follows, reference is made to the accompanying drawings, forming a part hereof, and in which—

Figure I is a side elevation of the improved crane. Fig. II is an end elevation of the same. Fig. III is a plan of Fig. I. Figs. IV and V are views of parts of the invention on an enlarged scale. Fig. VI illustrates a modified construction of the crane.

Similar letters of reference indicate similar parts in all the views.

In the said drawings, A is an elevated rail extending longitudinally of the building and near to one wall thereof. A second rail, corresponding to the one A, is similarly placed at the opposite side of the building, or, if the span is too great, in the center of the building, and supported by a series of columns. To avoid reducing the drawings to a too small scale, one rail only is shown.

B B are transverse girders placed parallelly side by side, and united at their ends by trucks C, having wheels D, adapted to run on the rails A.

E E are brace-rods to stiffen the girders, and their lengths are adjusted by means of right and left hand screw threads and nuts a, after the manner of ordinary truss-rods.

F is a wheeled frame, situated between the girders B, and extending to near the floor of the building. The wheels which directly support the frame F are denoted by b, and they are of the ordinary flanged truck pattern, secured to axles c, supported in suitable boxes in the frame.

G G are sheaves, adapted to turn loosely on the axles c. The lower end of the frame F is provided with hoisting machinery of the type usually employed in cranes of this class, and which needs no detailed description herein.

H is the spirally-grooved winding-drum of the hoisting apparatus, to which one end of the hoisting-chain d is attached. The chain extends directly over the sheaves G, and at its free end is provided with a hook, e, as shown.

All the bearings for the axles and the shafts carrying the truck-wheels D are fitted with anti-friction rollers. By extending the frame to near the floor and locating the hoisting apparatus as described the crane can be easily moved longitudinally and transversely of the building by hand, thus dispensing with the chains and other mechanical devices usually employed in overhead or traveling cranes for this purpose.

The hoisting apparatus is provided with a friction-brake. (Shown on an enlarged scale in Figs. IV and V of the drawings.)

The crane illustrated in Figs. I, II, and III, although applicable to buildings in which the longitudinally-moving girders extend entirely across the same, is especially designed for use where the girders extend only to the center of the building, and are supported by a track elevated on columns, as before alluded to. With this arrangement two complete frames with their hoisting apparatus are used.

In cases where the girders extend entirely across the building a double frame, such as is illustrated in Fig. VI of the drawings, may be employed with advantage. In this latter design the frame would have three sheaves, with a single chain attached at its center to the winding-drum. It is estimated that three coils of chain around the drum, in view of the weight of the end not in use, would be sufficient to prevent slipping of the chain in hoisting. The drum could, however, have a central notch for a link to fit into, if desired. The principal object of this double arrangement of the frame is to admit of objects being lifted from and deposited at all parts of the floor with a single frame, as will be readily understood.

Either of the hoisting-hooks, when not in use, may be suspended as shown in dotted lines, Fig. VI.

It will be understood that when one end of

the chain is hoisting the other is lowering; but this may be changed so as to make both ends of the chain hoist or lower at the same time by commencing to wind the chain at one side 5 of the hoisting-drum instead of at opposite sides, as shown.

I claim as my invention—

In a traveling crane, a pair of elevated rails, a pair of wheeled girders adapted for movement 10 longitudinally of the said rails, a frame sustained by wheels from the girders and extend-

ing downward to below the said girders and near to the floor of the building, a hoisting apparatus secured to the lower end of the said wheeled frame, and a series of sheaves for the 15 hoisting-chains attached to the said frame and in positions above the said hoisting apparatus, substantially as and for the purpose specified.

JOHN WALKER.
